UNITED STATES PATENT OFFICE.

OTIS A. MILLER, OF LAWTON, OKLAHOMA.

AUTOMATIC HYDRAULIC TREATING-TABLE.

1,205,649.

Specification of Letters Patent.

Patented Nov. 21, 1916.

Application filed August 12, 1916. Serial No. 114,546.

To all whom it may concern:

Be it known that I, OTIS A. MILLER, a citizen of the United States, residing at Lawton, in the county of Comanche and State of Oklahoma, have invented a new and useful Improvement in Automatic Hydraulic Treating-Tables, of which the following is a specification.

My invention relates to certain improvements in tables for the mechanical treatment of the human body.

It is the object of my invention to provide a table of this description comprising a pair of independently and relatively adjustable supporting members, together with hydraulically-operated means for effecting the various movements of which the parts of the table are susceptible.

It is a particular object of the invention to provide a table of this description capable of operating automatically to give the stretching or traction treatments which are advantageous in certain conditions.

The invention will be more fully understood from the following detailed description of a specific embodiment thereof, and from the accompanying drawings illustrative of the same.

In these drawings, Figure 1 is a side elevation of my improved table; Fig. 2 is a top plan view; Fig. 3 is a bottom plan view of the table-tops; Fig. 4 is a top plan view of the supports, the table-tops being removed; Fig. 5 is an enlarged vertical section through the movable head-end of the table, taken substantially on the line 5 of Fig. 4; Fig. 6 is an enlarged sectional view of the harness-adjusting drums, substantially on the line 6 of Figs. 3 and 5; Fig. 7 is an enlarged broken sectional view through one of the tilting cylinders; Fig. 8 is an enlarged sectional view through the stationary or foot end of the table, taken on the line 8 of Fig. 4; Fig. 9 is a transverse section on the line 9 of Fig. 8; Fig. 10 is an enlarged horizontal section through the controlling valves; Fig. 11 is an enlarged vertical section, partly in elevation, of the valve structures, the section being taken on the line 11 of Figs. 10 and 13; Fig. 12, a section on the line 12 of Fig. 11; Fig. 13 is a still further enlarged section, taken on the line 13 of Fig. 11, showing the automatic reversing controls for the valve and showing also, diagrammatically the fluid pressure circulating

system and the electrical control therefor; Fig. 14 is a sectional view, partly in elevation, of the reversing rod for the valve; and Fig. 15 is a section on the line 15 of Fig. 13.

Referring more particularly to the drawing, the numeral 20 designates the stationary supporting casting for the foot end of the table structure, and the numeral 21 designates the traveling support for the head-end. The latter member, which is carried by casters 22, is connected with the stationary standard 20 by a telescoping hydraulic cylinder and piston construction, the cylinder, designated 23, being secured in the stationary support 20, and the piston 24 in the traveling support 21, the construction and arrangement of these parts being best illustrated in Figs. 5 and 8. As will be noted from an inspection of the latter figure, the piston is of the single acting or ram type, being provided with the usual cup-leather 25, and for effecting the mechanical return of the piston, there is provided a helical spring 26 which encircles a rod 27 secured by a set-screw 28 in the stationary casting 20, the spring abutting at one end against a nut at the outer end of the rod and at the other end against the base of the piston.

The head and foot tables, designated 29 and 30, are each directly supported upon rams 31 and 32, respectively, operating in vertical bores in the base-members 21, 20. The rams, which are of identical construction, are provided at their lower ends with the usual cup-leathers, and, in addition, each ram carries means for positively limiting its upward stroke, such means comprising a small plunger 33 operating against a spring in a transverse bore 34 adjacent the lower end of the ram. The outer ends of the plungers are inclined downwardly, as shown, to coöperate with the oblique surfaces 35 of notches or grooves extending around approximately 180° of the periphery of the ram cylinders adjacent their upper ends. The plungers 33 are properly splined to secure them against rotation, and in order that they may at all times be held in the proper position, as shown in Figs. 5 and 8 of the drawings. By turning the rams 31 and 32 to such angular position as to take the plungers 33 out of the path of the grooves 35, the rams may run completely out of their cylinders, but in the normal position of the parts, the spring-pressed

plunger will engage the notch to positively lock the ram at the predetermined upward limit of movement.

Each of the table-tops 29 and 30 is secured to its ram by a horizontal pivot 36, and the outer or free ends of the two tops are supported by inclined telescopic, hydraulically-actuated struts, which are designated 37, 38 for the two tables, respectively. The lower end which forms the cylinder for each strut is secured by a fork 39 pivoted to a split ring 40 embracing, and rotatable upon, the supporting standard. To lock the ring, and, through it, the strut and table, against such rotation, there is provided a winged set-screw 41, which forms the pivot-bolt for one end of each fork, and passes completely through the ring 40 for engagement with the surface of the standard. The piston or plunger of each of the struts 37, 38 is provided with the usual cup-leather, as illustrated in Fig. 7, and, at the outer end, is pivoted to the under face of the table. For a purpose which will later appear, the strut 38 has formed thereon a hook 42 (Figs. 1 and 8) for coöperating with which the table 30 is provided with a pivoted shackle 43. A harness of any approved form may be used in connection with the tables 29, 30, and for purposes of illustration I have shown the table 30 as equipped with a waist-band 44 (Figs. 1 and 2), the tugs of which are brought together and secured by a pivoted hook 45 at the free end of the table, while the table 29 has a breast-strap 46 and a collar 47, each provided with two tugs or traces caught over pivoted eveners 49 which are attached to independent cables 50. The cables 50 pass through an appropriately curved tube 51 (Fig. 5), pivoted to the lower face of the head-end of the table, the cables being then extended rearwardly and wound upon independent drums 52 sleeved over a common shaft 53 extending transversely of the lower face of the table, the entire assembly being supported in brackets 54, as illustrated in Fig. 6. Each of the cable-drums 52 is provided with a ratchet-wheel 55 with which coöperate locking-pawls 56 which are normally held in engagement by springs, but may be released by hand-levers 57 secured to their shafts. The shaft 53 has pinned thereto between the opposed end faces of the drums 52 a driving-disk which carries pins 58 upon both faces, the space between the drums being sufficient to permit the pins to engage selectively with mating apertures in the drums, so that by axial movement of the shaft 53 it may be used for turning one or the other of the two drums.

For controlling the movements of the five hydraulically-actuated devices described, that is, the two struts, the two rams, and the telescopic connection between the sta-

tionary standard and the traveling standard, there is provided the valve arrangement illustrated in Figs. 10 to 15. A valve-casting 59, which may be mounted upon the stationary standard 20, is bored to form two conical valve-seats 60 and 61, with which coöperate taper plug valves 62, 63, which I call, respectively, the selector-valve and the master-valve. The selector-valve is provided with a single transverse bore 64, which communicates with a peripheral groove 65 at one end, and at the other end is adapted to be brought into registration with any selected one of five ports 66, each of which has connected thereto a pipe 67 leading to one of the hydraulically-actuated members, hose connections being employed for forming connections wherever required. The master-valve 63 has three communicating radial bores 68 therein, one of the bores being adapted to register selectively with an inlet-port 69 in the casting 59, with an exhaust port 70, or to be blanked by occupying a position intermediate these two ports. The other two bores 68 are arranged in proper angular relation to the first bore, so that one of the former will register with a communicating passage 71, leading to the selector-valve when the master-valve is in registration with either the inlet or outlet ports 69 and 70. When the master-valve occupies the intermediate position, the arrangement thus described will provide a double seal, that is, both the exhaust and inlet ports 69 and 70 and the communicating passage 71 will be blanked. The lower end of the master valve 63 is projected to form a squared stud 72, on which there is secured a disk 73 having in its periphery a pair of ratchet notches 74, with which coöperate pivoted locking-arms 75, the arms extending beyond the disk and having their extended ends coupled by a tension spring 76. The disk 73 also carries an arm 77, the free end of which has caught therein the ends of a pair of opposed springs 78 mounted upon a trip-rod 79 which telescopes within a supporting-tube 80 carried by the traveling standard 21, as shown in Fig. 1. A thumb-screw 81, provided in the outer end of the tube 80, may be loosened to permit the trip-rod to slide freely within the bore of the tube, or may be tightened to lock the telescoping-members together in any desired position of adjustment. A trip-lug 82 projects laterally from the trip-rod 79 into the path of the extended ends of the arms 75. The two arms 75 may be locked in a central position and sufficiently spread apart to clear both of the ratchet notches 74 by a pivoted latch-plate 83, which is adapted to engage over the ends of the arms, as shown in Fig. 15.

The electrical connections, as well as the hydraulic system employed in the apparatus

are diagrammatically illustrated in Fig. 13. For supplying fluid under pressure to the table-actuating means, there is provided an electric motor 84 driving, through a suitable gear train 85, a fluid pump 86. The outlet side of this pump is connected by a pipe 69' with the inlet 69 of the master-valve, while the inlet side of the pump is fed by a pipe 85' from a reservoir 86', into which the exhaust or outlet-port 70 of the master-valve discharges, as through the conduit 70'. The motor 80 is controlled by the actuation of the master-valve 63 through the switch mechanism illustrated in Fig. 13, which comprises a stationary spring contact 87 which lies in the path of a movable contact-arm 88 mounted upon, but insulated from, the disk 73. The contacts are so related as to come into engagement and thereby energize the motor 84 when the master-valve is in the position indicated by Fig. 10. In the cut-off or exhaust position of the valve, the contacts disengage and permit the motor to stop.

In general, my table is designed to provide means by which a human body may be supported in practically any position desired for treatment, such adjustment of the table being effected either before the patient is placed upon the table, or when he is resting there. Since practically all of the operative movements of the table which require any force are effected by hydraulic pressure, it becomes as easy to shift the position of the table while the patient is on the same as when the table is unloaded. In this respect, my device is superior to the manually-adjustable tables, in that, with the latter, it is more convenient, and, in fact, usually considered necessary, to set the table in proper position before the patient mounts the same. In general, the two sections which comprise my table are independently adjustable, as to height, inclination and horizontal angular position. Thus, for instance, the selector-valve 62 may be turned to such position as to register with the conduit connected with the cylinder of the traveling standard 21, and the master-valve 63 being then turned to the inlet position, the electrical contact will be closed between the points 87, 88, to start the motor 84, whereby fluid under pressure is admitted to lift the ram 31 and thereby elevate the head-end of the table 29. During such movement, the table will tilt upon its support on the strut 37. When the head end of the table has been brought to the proper position, the master-valve 63 will be turned to the cut-off position, the selector-valve rotated to register with the conduit communicating with the strut 37, and, the master-valve being again turned to the inlet position, fluid pressure will act to elongate the strut 37, thereby tilting the table-

section 29 upon its pivotal support 36. Similarly, the selector-valve having been placed in the appropriate position, the master-valve may be turned from the cut-off position to the exhaust-position, and the weight of the table will then act to force the ram 31 or the strut 37 downwardly, accordingly as one or the other has been selected. It is therefore clear that by proper manipulation of the selector-valve and master-valve, each of the two table-sections may be raised or lowered and fixed at any angular position within the range of the apparatus and at any horizontal level, the two table-sections being entirely independent of one another with respect to their movements and adjustments. And so, also, the traveling standard 21 may be moved toward or away from the stationary standard 20 to space the tables 29, 30, to bring them into any desired relationship by the proper operation of the selector-valve and master-valve. The operation of the cylinder and piston 23, 24, by which this last movement is effected, differs only from the operation of the other cylinders and pistons described in that the return of the traveling standard 21 is effected, not by gravity, but by the tension of the spring 26, which need only be of sufficient strength to overcome the frictional resistance of the parts in their movement in the horizontal plane.

In general, my table is adapted for all those uses for which devices of this kind are designed. The particular feature of the table, however, is the provision which is made for the automatic functioning of the same in carrying out stretching or "traction" treatments, in which the spine, or other portions of the anatomy of the patient, are to be subjected to periodic tension of a regulated amount. For carrying on such treatment in one way, the table-sections may be arranged in the position in which they are shown in the drawings, the patient being strapped or harnessed, as there illustrated. The latch 83 (Fig. 15), by which the two pawl-arms 75 are normally held in inoperative position, is released, and, the standard 21 having previously been adjusted in proper spaced relationship with the table 30, and the shackle 43 dropped over the hook 42 to prevent the strut 38 from further elongating, the trip-rod 79 is moved to the right, as viewed in Fig. 13, until the left-hand face of the trip-lug 82 is spaced away from the left-hand arm 75 by the distance through which it is desired the patient to be stretched. The set-screw 81 is then tightened, the selector-valve 62 is put into communication with the cylinder 23, and the master-valve 63 turned to the inlet position. The left-hand arm 75 now drops into the coöperating ratchet-notch 74, thereby locking the master-valve in the inlet position, and simultane-

ously the traveler 21 begins to move away from the stationary standard 20, thereby stretching the patient upon the table. In such movement, the trip-rod 79 will be carried to the left, while the arm 77 on the master-valve remains in the position indicated by the drawing, the springs 78 permitting this relative movement of the parts. At the predetermined limit of stretching, 5 the trip-lug 82 will contact the end of the pawl 75, releasing the latter from the ratchet-notch, and by the tension of the left-hand spring 78, the arm 77 will be quickly pulled to the left, thereby turning the master-valve to the exhaust position. The 10 spring 76 will simultaneously act to engage the right-hand arm 75 with the corresponding ratchet notch, and the valve will therefore remain locked in the exhaust position 15 while the traveler moves toward the stationary standard 20 under the influence of the spring 26. In this movement, as before, one of the springs 78 will be tensioned, and, at the limit of movement, the trip-lug 82 will 20 actuate the right-hand pawl, and the valve will snap back to the inlet position. The patient will therefore be alternately stretched and released for such period as is deemed necessary, the table acting automatically to 25 secure this result. The amount of stretching to be administered in any instance may be adjusted by adjusting the initial position of the trip-rod 79. The machine may be stopped at any time during the stretching 30 operations, either by moving the selector-valve 62 to a position in which it will blank the communicating passage 71, or by moving the master-valve manually. To reset the machine for normal operation, it is then only 35 necessary to loosen the set-screw 81, by which the trip-rod is locked, and to spring the pawl-arms 75 apart and secure them in such position with the latch 83.

While I have shown and described in considerable detail one specific embodiment of my invention, it is to be understood that this showing and description is illustrative only, and for the purpose of making clear the nature and objects of the invention, and that 45 50 I do not regard as essential any of such details.

The invention is not to be regarded as limited to the illustrative features shown, except in so far as such limitations are included within the terms of the following claims, in which it is my intention to claim all novelty inherent in my invention as broadly as is permissible in view of the prior art.

60 What I claim is:

1. A treating-table of the class described, comprising, in combination, a plurality of body-supporting surfaces, independent means for elevating each of said surfaces,

and independent means for adjusting the 65 inclination of each of said surfaces.

2. In a treating-table of the class described, a pair of supporting standards, longitudinally adjustable connections between said standards, a table-top carried by each 70 of said standards, and means for adjusting the inclination and elevation of each of said table-tops.

3. In a treating-table of the class described, 75 a stationary standard, a traveling standard, connections between the two standards for positively moving the traveling standard toward and away from the stationary standard, and a body-supporting surface carried by each of said standards.

4. A treating-table of the class described, comprising relatively movable body-supporting surfaces, a fluid-pressure cylinder connected with one of said surfaces and a 85 coöperating piston connected with the other surface, and means for controlling the supply of fluid to the said cylinder to effect relative movement of the two surfaces.

5. A treating-table of the class described, 90 comprising, in combination, a stationary standard having a body-supporting surface mounted thereon, a traveling standard having a body-supporting surface mounted 95 thereon, and telescoping fluid-pressure-actuated connections between the said standards for effecting relative movement thereof.

6. A treating-table of the class described, comprising a pair of relatively movable body-supporting surfaces, and automatically operable means for reciprocating said surfaces with respect to one another.

7. A treating-table of the class described, 100 comprising a stationary standard having a body-supporting surface mounted thereon, 105 a traveling standard arranged in spaced relation to the stationary standard and having also a body-supporting surface, telescopic fluid-pressure-actuated connections between the said standards, and means actuated by relative movement of the standards 110 for effecting continuous reciprocation of the traveling standard.

8. In a treating-table of the class described, 115 a base-member and a table-top, a fluid-pressure cylinder connected with one of said members and a coöperating piston connected with the other member, and a strut provided with means for adjusting the same longitudinally and having one end pivoted to said table-top at a point remote from the first-named support thereof and having its other end pivoted to the said base.

9. A treating-table of the class described, 125 comprising a base, a telescopic fluid-pressure-actuated vertical support mounted thereon, a table-top carried by said support,

and a telescopic fluid-pressure-actuated strut having one end connected with said table-top at a point remote from said first-named support thereof, and the other end 5 connected to said base.

10. A treating-table of the class described, comprising a pair of spaced base-sections, a vertically-adjustable support connected with each of said sections, table-tops each 10 having one end carried by such support, and extensible struts each having one end connected to one of said table-tops at a point remote from its first-named support and the other end connected with the cor- 15 responding base-section.

11. A treating-table of the class described, comprising a stationary base-section, a traveling base-section connected therewith for movement toward and away from the 20 stationary base, vertically-adjustable supporting members carried by each of said bases, a table-top having one end mounted on each of said supports, and an extensible strut connecting each of said table-tops with 25 the corresponding base-section.

12. A treating-table of the class described, comprising a stationary base-section, a traveling base-section, a telescopic fluid-pressure-actuated connection between said

sections, a hydraulic plunger mounted in 30 each of said sections, a table-top supported by each of said plungers, and a telescoping hydraulically-actuated strut connecting each table-top with its base.

13. A treating-table of the class described, 35 comprising, in combination, a base-member, a table-top adjustably mounted thereon, a plurality of fluid-pressure-actuated struts for effecting the adjustments of said top, means for supplying fluid under pressure to 40 said adjusting means, a selector-valve for placing said fluid supply selectively in communication with any one of said adjusting means, and an independently operable master-valve in series with said selector- 45 valve for admitting pressure to, or venting, the selected adjusting means.

14. In a treating-table of the class de- 50 scribed, and in combination, a base, a table-top supported thereon, fluid-pressure-actuated means for adjusting said table-top relatively to its base, a valve for controlling the admission of fluid to the said means, a fluid pump for feeding fluid under pressure to said valve, and means operable by move- 55 ment of the valve for controlling the operation of said pump.

OTIS A. MILLER.
